OIL BURNING DEVICE

Henry Horton Saunders, Newtown, Conn.

Application October 14, 1938, Serial No. 234,875

10 Claims. (Cl. 158—86)

This invention relates to oil burning devices, more particularly such as are used for water heaters, stoves, cook stoves, space heaters, portable room heaters, etc., and has for an object to improve the combustion to secure greater efficiency, or to complete the combustion with a minimum of odor and free carbon in the final products of combustion. It comprises primarily a wall of non-combustible material surrounding the burner or combustion chamber having a highly heat reflecting surface toward the burner or combustion chamber to reduce the radiation of heat laterally from the burner and to increase the temperature at the point of combustion.

In the accompanying drawing I have shown several types of oil burners or combustion apparatus with my invention applied thereto, these being shown by way of example, as it will be understood the same principle and improvement may be applied to other types of burners and combustion devices.

In this drawing:

Fig. 1 is a vertical section through one type of space or room heater showing a pot type of oil burner employing my improvement applied thereto;

Fig. 2 is a vertical section of a wick type of oil burner using a chimney and forming a blue flame burner, and with my improvement applied thereto; and

Fig. 3 is a similar section through a sleeve type blue flame perforated shell burner.

Referring first to the device shown in Fig. 1, although the pot type of the burner is shown as applied to a space or room heater it is adapted for use in water heaters, boilers, furnaces, etc. It comprises a pot having a side wall 5 surrounded by an air space 6 and having perforations 7 for flow of air from this space into the combustion space 8 within the pot. There is also preferably a top wall 10 extending inwardly from the top of the wall 5 any desired distance leaving a central opening 11 into the combustion or heating chamber 12.

Oil is fed from any suitable source of supply, not shown, through a pipe 13 and passage 14 to the bottom of the pot, where upon the application of a flame the oil is vaporized, mixes with air, supplied through the sides of the pot and burns, or if preferred a small amount of wicking 15 may be provided to become saturated with oil and ignited for starting the burner. The outer wall of the air space 6 is formed by an upright wall 16, the air entering the space 6 at its lower end 17. The inner surface of this wall indicated

5 at 18 is bright and highly heat reflecting. This bright highly heat reflecting surface may be formed in a number of different ways. It may be formed by making the wall 16 of metal having a highly polished heat reflecting surface or the wall 16 may be made of any of the usual materials such for example as sheet iron and have an inner lining of highly polished heat resisting and heat reflecting metal. The wall or the lining may be of such material as nichrome, stainless steel, or the like which will resist oxidation and disintegration due to the heat, or it might be aluminum foil or other bright metal. However, if aluminum foil is used there must be a reducing atmosphere as otherwise it will oxidize and disintegrate. In other words the highly heat reflecting inner surface 16 may be provided on the wall itself by polishing, or plating or coating the surface as by electrolysis or spraying of molten metal or other material, or a separate thin layer of the bright metal may be applied to the inner side of wall 16, or other heat resisting and reflecting material may be applied to this wall. Below the bottom wall 19 of the pot there may be a reflector plate 20 having a similar bright heat reflecting surface 21.

10 The wall 16 and the chamber 12 may be surrounded by an external casing 22 forming an air space 23 open at the bottom for entrance of air to be heated as indicated at 24, the heated air passing out through the top through suitable openings 25 in a top 26 on the casing. The final products of combustion from the chamber 12 may be led to a suitable flue or chimney by a pipe 27. The wall 10 at the top of the pot also may have openings 28 from the air heating space 6 to the combustion space above the wall 10 to further facilitate combustion. Combustion takes place within the space 8 or above the wall 10 or both depending on the rate of supply of oil to the pot.

15 Upon the application of flame oil is vaporized at the bottom of the pot above the wall 19, mixes with air in the pot and burns. As the combustion continues the surfaces of the pot including the walls 5 and 19 and the top wall 10 become heated causing increased vaporization of the fuel supply. Draft draws air in through the holes in the shell 5. This air mixes with the oil vapors and the combustion continues. The flame is present in the pot or above the pot or both according to the amount of the fuel supply. The final products of combustion pass out through the flue 27.

20 The bright or highly polished heat reflecting surface 18 reduces radiation outwardly from the

walls 16 conserving the heat to be used at or above the outlet from the pot through the wall 10. This highly reflecting surface also maintains an increased temperature in the space 6, more highly heating the air supply through this space before it passes through the holes 7 in the shell 5. This highly reflecting surface also increases the temperature of the shell 5 supplying additional heat to the air passing through the holes therein. The highly reflecting surface 21 below the bottom wall 19 reflects heat to this bottom wall causing quicker and more complete vaporization of the oil. When used in stoves, furnaces and the like the reflecting wall 18 reduces the heat in space 23 immediately around the burner, offering less interference with the circulation of air into the upper part of this heating space around the chamber 12 and increasing the over all efficiency of the unit. This highly reflecting surface reflects heat back toward the pot and the combustion space thus greatly increasing the temperature of the mixture of air and vapors over the ordinary type of burner, giving much better and more complete combustion with higher combustion temperatures, reducing to a minimum odors and incompletely burned carbon or other elements in the final products of combustion. This construction and arrangement increases the combustion efficiency of the burner and the over all efficiency of the unit in which it is used.

In the type of burner of Fig. 2 a similar effect is secured. This is a wick type of blue flame burner with a chimney. The wick is indicated at 29 in the space between two shells 30 and 31 to which oil is supplied through a pipe 32 from any suitable source of supply not shown. Surrounding the upper end of this wick is a baffle wall 33 forming an air passage 34 between this wall and the wick open at its lower end 35 for entrance of air. Surrounding this baffle and spaced therefrom and extending upwardly a suitable distance above the same is a chimney 36, the inner surface 37 of which is a bright highly heat reflecting surface which may be formed in any of the ways suggested for providing the bright heat reflecting surface 18 of the device of Fig. 1. The connecting wall 38 between this chimney and the baffle 33 has air inlet openings 39 leading to the space 40 between these elements. The upper wall of the chimney is usually inclined inwardly somewhat as shown at 41 to provide a somewhat reduced outlet opening 42. The highly heat reflecting surface 37 may or may not be applied to the inner side of this wall as desired. Within the inner wall 31 is a sleeve 43 having a top wall or cap 44 having perforations 45 for passage of air. This preferably extends somewhat over the top of the wick forming a passage 46 for entrance of heated air and oil vapors into the combustion space 47. The sleeve 43 may be supported in any suitable way. In the present showing it is mounted on a transverse rod 48 mounted in the wall 31. The lower end of the passage 49 within the wall 31 and the sleeve 33 is open at its lower end for inward flow of air to be heated to support the combustion on passing through the openings 45.

Upon the application of the flame oil is vaporized at 46 at the upper end of the wick. This vapor mixes with the air entering through passage 34 and is burned. Heat is carried to the wick chamber 30, 31 causing quicker vaporization and heating of the air flowing through the passage 49 and the sleeve 43 which rises to the

cap 44, and also passes into the space 46 through a passage 50 between the sleeve and the inner wall 31 in proximity to the wick which is giving off vaporized oil. This with air entering through the passage 34 continues the flame at the point 46, and in the chamber 47 this air also being heated from the wick chamber and the baffle 33. The highly heat reflecting surface 37 reduces lateral radiation from the chimney 36 conserving and reflecting the heat back to the wick and combustion spaces 46 and 47. It conserves the heat to be used at or above the outlet 42 and maintains a higher combustion temperature in the space 47. By reflecting heat to the wick chamber and the sleeve 43 the temperature in this wick chamber and sleeve is raised, causing the air supply to become hotter, and causing quicker and more complete vaporization of the oil, thus causing more complete and quicker combustion of the oil and air mixture at 46. Heat is radiated to this point by the bright reflecting surface maintaining the temperature of the flame to its complete combustion.

By this construction and arrangement the combustion efficiency is raised creating higher temperatures above the outlet 42 with a minimum of odor and free carbon in the final products of combustion. This burner is adapted for use for cook stoves, portable room heaters, water heaters, etc.

In Fig. 3 is shown another type of burner generally known as the sleeve type blue flame or perforated shell burner. It is adapted for use in cook stoves, portable room heaters, water heaters, etc. and also for all range burners. It comprises one or more spaced perforated shells 51 and 52 with a combustion space 53 between them and a wick 54 at the lower part of this space. This may be a short annular wick in a trough at the lower end of this space, or it may be a deeper wick of the type shown in the drawing extending into an oil chamber between the shells 55 and 56 to which oil is supplied from any suitable source of supply, not shown, by the pipe 57. The shells 51 and 52 may be supported in the usual manner, but in the present case are shown as mounted on shoulders on the flanges 58 and 59 at the upper edges of the shells 55 and 56.

Spaced from and surrounding the outer shell 52 is a cylinder or casing 60 having a highly polished or highly heat reflecting surface 61, which may be the surface of the casing or applied thereto or otherwise formed in any of the ways suggested for forming the heat reflecting surface 18 of the device of Fig. 1. There may be a lower wall 62 at the lower end of the space 63 between the shell 52 and the casing which has air inlet openings 64. There may also be an inwardly inclined top wall 65 at the upper end of the casing 60 having an outlet 66 for the flame and products of combustion, and the highly heat reflecting surface 61 may be extended to cover the inner surface of this top wall. The inner passage 67 through the wick chamber may be open at its lower end for the entrance of air passing through the inner side of the shell 51 and supplying air to the perforations in the shell. Within this shell and spaced a suitable distance therefrom and forming an air inlet and combustion passage 68 is preferably located a drum 69 provided on its outer surface facing the shell 52 with a bright heat reflecting surface 70 similar to the surface 61 on the inner wall of the casing 60. The shell 60 and the drum 69 may be mounted in any suitable manner, but in the present case

are shown as mounted on transverse rods 71 and 72 passing through the shells 51 and 52.

In this construction the heat vaporizes the oil from the wick in the lower part of the passage 53. The oil vapors and air are mixed in this passage between the shells 51 and 52. The mixture being in contact with these shell surfaces combustion will take place, and if the shells are raised to a proper temperature these shells will become catalysts thus further assisting in the combustion. If the shells are raised to a sufficiently high temperature the combustion is complete and there is a minimum of disagreeable odors and free carbon present in the products of combustion. The bright reflective surface 61 reduces heat radiation from the shell 60 conserving and increasing the heat to be used at and above the outlet 66, and the combustion temperature of the space 53 is maintained at a higher point. By reflecting heat back from the surfaces 61 and 70 toward its source the temperature of the source is raised and a higher temperature is maintained at the shells 51 and 52, and in the space 53. Also, the air supply through the spaces 63 and 68 is more highly heated giving it a higher temperature before being mixed with the oil vapors thus still further increasing the temperature of combustion. Furthermore the vaporizing chamber at the lower part of the space 53 and the wick chamber are heated to a higher degree causing a quicker and better vaporization of the oil, and such vapor being hotter burns faster and more completely. Under the top wall 65 from its inner surface 61 heat is radiated to the rising flame maintaining its temperature to its complete combustion.

By the above construction and arrangement the combustion efficiency is raised, creating higher temperatures at and above the outlet 66, with the result that there is greater heating efficiency and there is a minimum of odors and free carbon in the final products of combustion.

A similar result is secured by the higher heat reflecting surface in all of the forms shown, and it will be evident the same result can be secured by supplying such surface about other types of oil burners to reflect the heat back into the flame and the point of combustion of the mixed air and vapors, thus greatly increasing the temperature of the combustion and giving a more complete and thorough combustion with higher efficiency and less disagreeable odors in the products of combustion.

Having thus set forth the nature of my invention, what I claim is:

1. In an oil burner, an upright combustion chamber in which oil is vaporized by heat at the lower part thereof, means for feeding air to the vaporized oil, and an upright wall surrounding said chamber having a bright highly heat reflecting surface toward said chamber to reflect a large amount of heat back toward the chamber at the zone of combustion.

2. Combustion apparatus of the character described comprising a burner chamber having an upright surrounding side wall, means for supplying oil to the lower part of said chamber to be vaporized therein, means for supplying air to the vaporized oil for combustion thereof, and an upright wall surrounding and spaced from the first wall forming a passage for supply of air to support combustion and having a bright highly heat reflecting surface toward said chamber and arranged to reflect a large amount of heat back

toward the zone of combustion in said chamber.

3. In a combustion apparatus of the character described, an upright burner chamber, means for supplying oil to the lower part of said chamber to be vaporized therein, means for supplying air to the oil vapor for combustion thereof, and an upright wall surrounding said chamber having a surface of non-combustible material and which is bright and highly heat reflecting arranged to reflect heat back toward said chamber at the zone of combustion.

4. In a combustion apparatus, an oil burner comprising a pot closed at the bottom and having a perforated side wall, means for supplying oil to the bottom of the pot, an upright wall surrounding and spaced from said perforated wall forming an air space for supply of air to said perforations, and said upright wall having an inner surface of highly heat reflecting material to reflect heat back toward the perforated wall.

5. In a combustion apparatus an oil burner comprising a pot closed at the bottom and having a perforated side wall, means for supplying liquid fuel to the bottom of the pot, an outer upright wall spaced from the perforated wall forming an air supply passage to the perforations, the inner surface of said outer wall being a bright highly heat reflecting surface, a baffle plate spaced below the bottom wall of the pot, and said plate having a bright highly heat reflecting surface toward the bottom of the pot.

6. In an oil burner, a wick chamber and a wick in the chamber, means for supplying oil to the wick, a baffle surrounding the wick chamber and forming a passage for air to the chamber at the top of the wick, and a shell surrounding the chamber and baffle and extending above the same, said shell having a bright highly heat reflecting surface on its inner wall to reflect heat back into the wick chamber and the space above this chamber.

7. In an oil burner, a pair of spaced perforated shells forming a combustion chamber between them, means at the lower part of this chamber for supplying oil for vaporization therein, a casing surrounding the outer shell and spaced therefrom, there being passages for supply of air to the space within the inner shell and the space between the casing and the outer shell, and the inner surface of the casing being of highly heat reflecting material to reflect the heat back toward the perforated shells.

8. In a combustion apparatus an oil burner comprising a pair of spaced perforated shells forming a combustion space between them, means for supplying liquid fuel to the lower part of this space for vaporization therein, a casing surrounding the outer shell and spaced therefrom to form an air passage, a drum within the inner shell and spaced from this shell to form an air passage, and the inner surface of the casing and the outer surface of the drum being of bright highly heat reflecting material to reflect the heat back into the shells.

9. In a combustion apparatus of the character described, an oil burner comprising a burner chamber having a perforated upright side wall, means for supplying oil to said chamber to be vaporized therein, an upright wall surrounding and spaced from the perforated side wall forming an air space for supplying air to said perforations for supply of air to the vaporized oil for combustion thereof, and said second wall having a bright highly heat reflecting surface toward

said perforated wall arranged to reflect heat back toward the perforated wall.

10. In a combustion apparatus, an oil burner having a combustion space and an upright wall around said space providing means for supplying air to said space for combustion of vaporized oil therein, means for supplying oil to said space to

be vaporized therein, an upright wall surrounding the first wall and forming therewith an air passage for supply of air for combustion, and said second mentioned upright wall having an inner surface of bright highly heat reflecting material to reflect heat back toward the combustion space.

HENRY HORTON SAUNDERS.
